UNITED STATES PATENT OFFICE.

JOHN C. McBRIDE AND TOM A. BLAIR, OF BOULDER, COLORADO; SAID BLAIR ASSIGNOR
TO SAID McBRIDE.

MERCHANDISE-VENDING MACHINE.

1,052,607.

Specification of Letters Patent. Patented Feb. 11, 1913.

Application filed December 26, 1911. Serial No. 667,860.

To all whom it may concern:

Be it known that we, JOHN C. McBRIDE and TOM A. BLAIR, citizens of the United States, residing at Boulder, county of 5 Boulder, and State of Colorado, have invented certain new and useful Improvements in Merchandise-Vending Machines; and we do declare the following to be a full, clear, and exact description of the invention, 10 such as will enable others skilled in the art to which it appertains to make and use the same, reference being had to the accompanying drawings, and to the characters of reference marked thereon, which form a part 15 of this specification.

Our invention relates to improvements in machines for vending merchandise by the use of a coin, which, when inserted, serves to actuate the mechanism to release a package of whatever kind the machine is constructed to deliver.

Our improved device, as illustrated in the drawing, is more especially designed for vending newspapers, though it is evident 25 that it may be employed to advantage in vending various other articles of merchandise.

The invention is especially adapted for use in vending newspapers, since it may be 30 permanently located in hotels and other public places, thus making it practicable to obtain newspapers at any time during the day or night, and thus making it unnecessary to wait for news boys or visit newsstands, the latter being only open during 35 specified hours of the day. Furthermore, our improved machine has an additional advantage, since the papers delivered thereby are always perfectly clean, not having been 40 handled by news boys or others. It very frequently happens that papers, when bought upon the street, are considerably soiled and injured. All of this is obviated by the employment of our improved merchandise vending apparatus.

Our improved construction is adapted to automatically deliver a newspaper whenever a coin is inserted in the coin slot. Furthermore, provision is made whereby it becomes 50 impossible to secure a paper by the introduction of a wrong coin, since the latter will not follow the chute necessary in order to actuate the paper delivering mechanism.

We have, however, devised a form of construction adapted to be used by two pennies 55 in succession, whereby such papers as it is desired to sell at two cents each may be obtained from the machine.

Still another important feature of the machine consists of the construction whereby, when the paper holding carriage has moved forwardly to its limit of movement and has discharged all of the papers originally placed therein, a plate will be automatically placed in position to close the coin 65 slot, the word "Empty" being visible on the plate in front of the slot to notify the would-be customer of the cause of such closure.

Having briefly outlined our improved 70 construction, we will proceed to describe the same in detail, reference being made to the accompanying drawing, in which is illustrated an embodiment thereof.

In this drawing: Figure 1 is an elevation 75 of the device with the side-door open, the mechanism within being partly broken and partly in section. Fig. 2 is a horizontal section, taken on the line 2-2 of Fig. 1. Fig. 3 is a fragmentary top plan view of a 80 portion of the construction shown in Fig. 2, but on a larger scale. Fig. 4 is a fragmentary view partly in section and partly in elevation, illustrating the mechanism disclosed at the lower lefthand corner of Fig. 1, 85 the parts, however, being shown on a larger scale. Fig. 5 is a fragmentary view of the forward part of the construction, or the part shown at the right of Fig. 1, but on a larger scale. Fig. 6 is a view partly in elevation and partly in section of the upper righthand corner of the mechanism shown 90 on the same scale as in Fig. 1. Fig. 7 is a fragmentary top plan view of the construction, the casing being shown in horizontal 95 section, the parts being illustrated on a larger scale than in Fig. 2. Fig. 8 is a fragmentary enlarged detail view of the carrier. Fig. 9 is a detail view of the spring for actuating the carrier, the shaft or spindle 100 with which it is connected at one extremity being shown in cross section, which is also true of the portion of the casing with which the spring is connected. Fig. 10 is a view similar to Fig. 1, but illustrating a modified 105 form of construction. Fig. 11 is a sectional

detail view illustrating the manner of mounting the carrier on its support. Fig. 12 is a detail view of two sprocket wheels having different numbers of teeth.

5 The same reference characters indicate the same parts in all the views.

Let the numeral 5 designate a casing, which, as illustrated in the drawing, is provided on one side with a door 6, hinged at 10 7. A second door 4 is provided at the back of the casing and extends to the floor thereof. When the door 6 is open, the operating mechanism is disclosed. This mechanism will now be described.

15 The mechanism within the casing 5 may be so located that it is entirely removable therefrom and capable of being placed in a suitable housing of any kind. Hence, it will be understood that the mechanism may be 20 inclosed and constitute a part of a cigar-stand cabinet or other similar or suitable structure conveniently located for dispensing newspapers or other articles.

Suitably journaled within a frame 8 located within the casing or other housing is a shaft or spindle 9. As illustrated in the drawing, the extremities of this spindle are journaled in upright parts 10. Mounted and made fast on the shaft near its opposite 30 extremities are two sprocket wheels 12, which are engaged by chains or other suitable flexible devices 13, the extremities of the said chains being respectively connected with the extremities of a carrier member 14 composed of sections 15 hinged together, as shown at 16, whereby the carrier is made sufficiently flexible to pass around a rotary bar 17 located at the forward extremity of the horizontally-disposed bars 18 forming a 35 support for the carrier. These carrier sections, as illustrated in the drawing, are constructed to receive newspapers or other suitable or similar articles or packages 19. It is intended, however, in this application, to 40 illustrate a construction particularly adapted for use in vending newspapers, and the specific construction disclosed should, therefore, be considered with special reference to dispensing papers.

45 Slidably mounted on the bars 18 and connected with the rear extremity of the carrier 14 are two upright members 20, which form a support for the papers in the rear. The carrier is adapted to receive as many papers 50 as there are sections 15.

A coiled spring 21 is connected at one extremity with the shaft 9, as shown at 22, its opposite extremity being secured to the frame 8 within the casing, as shown at 23.

55 Also fast on the shaft 9 is a ratchet wheel 24, the teeth of which are engaged in the rear by a pawl 25 pivoted as shown at 26 on a stationary part 27. The upper extremity 28 of this pawl is pivotally con-

nected with the body of the pawl, as shown 65 at 29, the part 28 being engaged by a spring 30 secured to the body of the pawl at one extremity, as shown at 31. This spring is sufficiently stiff to make the part 28 substantially a rigid part of the pawl, so far 70 as its general function is concerned. The object of the yielding part 28 is to make it practicable to turn the shaft 9 to wind the spring 21 without operating the body portion of the pawl 25, together with other 75 parts connected therewith, as hereinafter explained.

On the opposite side of the ratchet wheel 24 from the pawl 25 is located a pawl 32, which is U-shaped in cross section, its closed 80 side being open, as shown at 33, to receive the teeth of the ratchet wheel. This pawl 32 co-operates with the pawl 25 in controlling the rotation of the ratchet wheel under the influence of the spring-actuated shaft 85 9, the latter having a normal tendency to rotate in a direction to unwind the spring. The two pawls 25 and 32 are connected by a link 34, the extremities of the link being pivotally connected with the pawls, as shown 90 at 35 and 36, respectively. The pawl 32 is pivotally connected with the stationary part 27, as shown at 37.

Connected, as shown at 38, with the upper extremity of the pawl 32, is the rear extremity of a rod 39, whose forward extremity is pivotally connected, as shown at 40, with one arm of a bell-crank lever 41 fulcrumed at 42, its opposite arm being pivotally connected, as shown at 43, with the 100 lower extremity of a rod 44, whose upper extremity is pivotally connected, as shown at 45, with a lever 46 fulcrumed at 47. This lever 46 is of the general shape of a bell crank, but has a relatively long arm 48 105 which extends downwardly from its fulcrum, its lower extremity terminating below the bell crank lever 41. Connected with the lever arm 48, intermediate its extremities, as shown at 49, is an arm 50, which is forwardly inclined from the lever arm 48, its lower extremity being connected with the lower end of the lever arm 48 by a part 51. Normally, the arm 50 protrudes into the lower extremity of a coin-chute 52, whose 110 mouth registers with an opening in a coin receptacle 53. The body of this coin-chute (see Fig. 1), extends vertically upwardly in the forward part of the casing, its upper part extending rearwardly, as shown at 54, 115 and thence upwardly, terminating in a part 55 forming an angle 56 with the part 54. A branch chute 57 communicates at its forward extremity, which is open, with an opening 58 formed in the upper part of the 120 casing, said opening being adapted to receive a coin for operating the device. The 125 opposite extremity of the branch-chute 57

communicates with the upper extremity 55 of the main coin-chute 52. This branch chute 57 has upper and lower flanges 59 and 60, which are so arranged as to engage the 5 upper and lower edges of the coin which is to be employed in operating the mechanism. It is assumed that the coin used will be a nickel. Hence, when a nickel is inserted in the opening 58, it will follow the branch 10 chute 57 into the part 55 of the main coin-chute, thence through the part 56 and finally through the vertically-disposed body part of the chute, passing downwardly where it engages the part 50 connected with the lever 15 arm 48, as heretofore explained. The weight of this coin acts to force the lever arm 48 rearwardly and raise the short arm 45 of the lever 46, thus lifting the rod 44 and actuating the bell crank lever 41 to 20 move the rod 39 rearwardly sufficiently to swing the pawl 32 toward the ratchet 24 to cause a tooth of the said ratchet to enter the opening 33 of the pawl above the edge 61 of the pawl below the said opening. At 25 the same time, the pawl 25 is moved rearwardly from the ratchet 24 sufficiently to disengage its upper extremity from the said ratchet, allowing the latter to make a partial rotation in the direction of the arrow α , 30 (see Fig. 4), until a tooth 63 of the ratchet engages the pawl 32 at the bottom of the opening 33. The pawl 32 then locks the ratchet against movement until the last-named pawl is moved forwardly through 35 the instrumentality of a spring 64, which is connected at one extremity with the upper part of the pawl 32, and at its opposite extremity with the rear end of a rod 65, the opposite end of the rod being secured, as 40 shown at 66, to a stationary part of the framework.

Every time a coin passes through the chute 52 and acts upon the lever 46, as heretofore explained, the operation just described is repeated, and the shaft 9 is allowed, under the influence of its spring 21, to make a sufficient rotation to allow the carrier 14 to move forwardly far enough to discharge a paper 19, or other article, at the 45 forward extremity of the machine, the latter having a passage 67 through which the paper is allowed to fall downwardly and escape at the bottom of the machine through an opening 68.

55 As illustrated in the drawing, the rotary bar 17 makes a quarter rotary movement every time the carrier is released, through the instrumentality of a coin, as heretofore explained. This rotary action of the bar 17 is sufficient, after the paper 19 has reached the foremost position indicated by dotted lines in Fig. 8, to drop the paper into the space 67 and allow it to fall through the opening 68, as heretofore described. The

number of sides of the bar 17 may be regulated, as desired. In other words, for a given movement of the carrier, each section 15 of the carrier, when it reaches the bar 17, may be caused to make either a quarter or a third of a rotation, or any other desired part of a revolution, depending upon the number of sides which the bar contains. It is desirable to have this bar so constructed as to positively insure the throwing of the paper into the space 67, whereby it is caused 70 to completely clear the carrier. At one extremity of the shaft 9, being that which is exposed when the door 6 is opened, is located a disk 69, which is made fast to the shaft and provided with numerals from 1 75 to a numeral indicating the number of papers which the device is adapted to hold. This disk is of sufficient size to form a convenient means, when grasped by the hand of the person in charge of the machine, for 80 rotating the shaft 9 in the direction the reverse of the arrow α , (see Fig. 4), for winding the spring 21. When the carrier is at its rearward limit of movement, the numeral 1 is just in the rear of a peep-hole 70 formed 85 in the door 6, which, of course, is then in the closed position. As each paper drops from the machine, the carrier, and consequently, the upper part of the disk 69 makes a forward movement, the movement of the 90 disk being just sufficient to bring an additional numeral on the disk into range with the peep-hole 70, hence, by looking through this peep-hole at any time, the number of papers sold may be ascertained.

When the carrier 14 has traveled to its forward limit of movement and all the papers have been discharged from the machine, a projection 71, carried by one of the upright parts 20 of the carrier, engages the forward 100 extremity 72 of a bell crank lever 73 fulcrumed at 74, the opposite extremity 75 of this lever being connected by means of a rod 76 with a plate 77, which normally occupies a position below the coin opening 105 58 of the casing. The movement imparted to the bell crank lever 73, when engaged by the projection 71, as aforesaid, is sufficient to actuate the rod 76 and lift the plate 77 to close the opening 58 to prevent the entrance of a coin after all the papers have 110 been discharged from the machine. This plate preferably carries on the part exposed through the coin opening, the word 115 "Empty," which notifies the would-be customer that there are no more papers in the machine.

In order to prevent the possibility of tampering with the machine by inserting an instrument upwardly through the opening 68, 120 the lower part of the space 67 is inclosed in the front and rear by walls 79 and 80. A plate 81, normally closes the space 82 between the

walls 79 and 80, this plate being hinged, as shown at 83, and normally held in the closed position by an arm 84 carrying a counter-balance weight 85. This weight holds the 5 edge of the plate 81, remote from the hinge, in engagement with the lug or seat 78, thus preventing the part 81 from being moved upwardly. Hence, this plate prevents the introduction of an instrument through the 10 bottom opening 68 far enough to enable the user to tamper with the machine.

Forward of the space 67, into which the papers or other articles fall, when discharged from the carrier, are located upper and 15 lower horizontally-arranged grooves 86 and 87 adapted to receive a plate 88 to which a paper, magazine or other article may be applied, the same being visible through the glass plate 89 set into the front wall of the 20 casing. This article may be fixedly connected with the plate 88, whereby a person who glances at the front part of the casing may readily see the character of the contents of the machine. This plate 88 is readily re- 25 movable, when the door 6 is open, and the article thereon may be quickly changed, if it is desired to displace the contents of the machine and substitute other papers, magazines or articles of any character.

30 The arm 50 connected with the lever 46, as heretofore explained, is so arranged that it enters both of the chutes 95 and 52 in such a manner that a coin passing through either chute will actuate the lever 46 to 35 release the carrier and allow the latter to make a step-by-step movement, as heretofore explained, assuming that pennies are successively employed to obtain papers or other articles from the machine, as hereto- 40 fore explained.

From the foregoing description, the use and operation of our improved construction will be readily understood. Assuming that the carrier is at its rearward limit of movement, as indicated in Figs. 1 and 7, it is 45 only necessary to open the door 6 in order to fill the machine with papers, which may be set edgewise in the sections 15 of the carrier, as indicated by dotted lines in Fig. 50 3. The door is then locked, and the device is ready for use, assuming that the shaft 9 has been actuated to wind the spring 21. Then, if a nickel is inserted in the opening 55 58, whereby it is caused to enter the branch chute 57, it passes downwardly therethrough and engages the part 50 to actuate the lever 46 and release the shaft 9 by virtue of the connection between the lever 46 with the parts 44, 41, 39, 32 and 25. During 60 this operation, the rod 39 is thrust rearwardly, imparting corresponding movements to the pawls 32 and 25, whereby the latter is disengaged from the ratchet 24, while the pawl 32 is placed in the path

of a tooth 63 of the said ratchet in such 65 position as to allow the latter to move half the distance of a tooth. As soon as this occurs, the action of the spring 64 will reverse the movement of the rod 39, allowing the ratchet to complete its partial rotation, 70 whereby it is allowed to travel the length of a single tooth, after which the pawl 25 will engage the next tooth and again lock the ratchet against movement, until the next coin is inserted. 75

Referring again to the rotary bar or shaft 17, attention is called to the fact that, as illustrated in the drawing, this shaft is square in cross section, and its faces are of the same area and arranged to fit the inner or adjacent faces 104 of the merchandise-carrying sections 15. By virtue of this arrangement, as this shaft or bar extends the entire width of the carrier, the hinges of the carrier members coincide as to position 85 with the corners of the bar 17, and, by virtue of this arrangement, the carrier sections are accurately aligned in a transverse direction with the sides or faces of the said bar, and, by virtue of this construction and 90 arrangement, it is impossible for the carrier sections to get out of accurate transverse alignment. This is a very important feature, since it is desirable that, when the paper or other article is discharged, or in 95 position to be discharged by the carrier, every part of the carrier section should release the paper or other article at the same time, and this condition must exist where the paper-carrying sections are kept in accurate alignment with the shaft or bar 17. 100

In order to lock the coin-box or receptacle 53 in place within the casing, we employ two plates 105 and 106, which are hinged together at 107. The plate 105 extends upwardly from the hinge 107 and is provided with an opening adapted to receive a lug 108, with which one end of the box 53 is provided. This lug, after passing through the opening in the plate 105, is equipped with a padlock 109, the hasp of which is passed through an opening 110 in the lug. The plate 106 normally occupies a horizontal position lying flat upon the bottom of the casing, and its extremity, remote from the hinge, is hinged, as shown at 112, to a stationary part 113. Now, when it is desired to remove the box, it is only necessary to open the door 6 and unlock the padlock. After this is done, the plate 105, by virtue 11 of its hinged connection with the plate 106, may be disengaged from the lug 108, after which the two plates 105 and 106 may be swung toward the left on the hinge 112, thus 12 getting these parts out of the way and making room for the removal of the coin box 53. 12

The upright members 20, forming a support for the papers in the rear, as hereto-

fore explained, are equipped with sleeves 120, which closely fit the supporting bars 18 and slide freely thereon in telescoping relation, thus forming a firm connection 5 with the said bars and preventing the carrier sections from getting out of transverse alinement.

In the form of construction shown in Figs. 10 and 12, provision is made for 10 handling relatively large papers, as Sunday papers, which would be too large to enter a single section 15 of the carrier. In this event, an auxiliary sprocket wheel 121 is employed, the regular sprocket 24 being 15 moved out of alinement with the pawls 25 and 32, and the sprocket 121 moved into alinement with said pawls. In order to do this, it is only necessary to remove a pin 122, which fastens the sprocket 24 to the 20 shaft 9, slide the sprocket 24 out of the way, and move the sprocket 121 into its place and secure it to the shaft by means of a pin or other suitable fastening device. The teeth of the sprocket 122 are far enough 25 apart to allow the carriage to travel the width of two sections 15 of the carrier every time the shaft 9 is released by the introduction of a coin in the manner heretofore explained. Furthermore, in order to make it 30 practicable to place the large papers on the carrier, the flanges 123 are cut away, as shown at 124, of every other section at one extremity, or at one side of the carrier, making room for the folded end of the Sunday 35 paper, so that it may lie flat on the bottoms of two carrier sections, thus allowing the two parallel parts of the paper connected by the bend to occupy two of the small sections 15 ordinarily occupied by separate week-day 40 edition papers. In this manner, and by only a slight change in the mechanism, our improved machine is adapted for use with papers of any size, from the largest to the smallest.

45 Attention is called to the fact that our improved merchandise vending machine is entirely devoid of exposed operating levers or other devices. Neither are there any openings communicating with the interior mechanism, except the peep-hole 70 and the coin slot 58.

Attention is called to the fact that the 55 member of the device in which the newspapers or other merchandise are directly placed, the same being composed of the sections 15, must in this specification be considered one member of an endless carrier, the other member consisting of the flexible devices or chains 13, whose extremities are 60 connected with the opposite ends of the carrier member proper, or the portion of the endless carrier which is directly engaged by the merchandise handled by the machine.

The sprocket wheels 24 and 121 may both

be formed on the same hub, or they may be 65 formed separately, as may be desired. If formed on the same hub, a single locking pin might be employed, the shaft being provided with separated openings to register with the opening in the hub when the 70 sprocket device is in either position.

Having thus described our invention, what we claim is:—

1. In a vending machine for newspapers or the like, a casing, an endless horizontally 75 disposed carrier supported at the end adjacent the front of said casing upon a horizontally disposed shaft, polygonal in cross section, said endless carrier being composed partly of receptacles, the bases of said receptacles being hinged together and having surfaces of equal area with the faces of said shaft, each of said receptacles having also a front wall adapted, when its receptacle passes over said shaft, to form a positive 85 means for dislodging a paper from the receptacle in front.

2. In a vending machine of the class described, the combination of a spring-actuated shaft, a ratchet wheel fast on said 90 shaft, pawls engaging the ratchet wheel and normally locking the shaft against movement in response to the tension of its spring, an endless carrier having a merchandise-holding portion, and a portion composed 95 of flexible devices, whose opposite extremities are connected with the merchandise-holding portion, wheels fast on the said shaft and engaged by the said flexible devices, the merchandise-holding portion of 100 the carrier being composed of hinged sections having inner flat faces, and a second shaft rotatably mounted at the end of the carrier remote from the spring-actuated shaft, the second shaft being polygonal in 105 cross section and whose faces are shaped to fit the inner adjacent faces of the sections of the merchandise-holding part of the carrier, and suitable means for intermittently releasing the shaft at properly timed intervals to allow the carrier, under the influence of the actuating wheels carried by the spring-actuated shaft, to make a step-by-step movement, substantially as described.

3. In a vending machine, the combination 115 with a spring-actuated shaft, of a ratchet wheel fast on said shaft, an escapement for said ratchet, one of the pawls of said escapement having a pivoted portion at its end normally held in engagement with the 120 ratchet by means of a spring and which when withdrawn against the action of the spring permits the shaft-actuating spring to be rewound without disturbing the other pawl and parts connected therewith.

4. In a vending machine, the combination 125 with a spring-actuated shaft, a plurality of ratchet wheels slidably arranged on said

shaft, means for locking any one of said ratchet wheels to rotate with said shaft, an escapement for engaging said locked ratchet wheel and normally holding the shaft 5 against rotation by the spring, an endless carrier, and wheels fast on the said shaft and engaging one extremity of the said endless carrier.

In testimony whereof we affix our signatures in presence of two witnesses.

JOHN C. McBRIDE.
TOM A. BLAIR.
